UNITED STATES PATENT OFFICE.

TRUMAN J. PEARCE, OF OAKLAND, CALIFORNIA, ASSIGNOR OF ONE-HALF
TO LESTER BISHOP, OF SAME PLACE.

LIFTING-JACK.

SPECIFICATION forming part of Letters Patent No. 268,371, dated November 28, 1882.

Application filed May 15, 1882. (No model.)

To all whom it may concern:

Be it known that I, TRUMAN J. PEARCE, of Oakland, in the county of Alameda and State of California, have made and invented a new and useful Improvement in Lifting-Jacks; and I do hereby declare that the following is a full, clear, and exact description of the same, reference being had to the accompanying drawings.

10 My invention relates to an improved construction of lifting-jacks for carriages, wagons, and other light work. The object sought to be attained is to produce a strong and durable implement at a low cost, and to afford better 15 facilities for handling and operating it in position where application of the power required to work it cannot be readily or directly made in the line of the actuating-lever. These objects I attain in the manner which I will now 20 proceed to describe.

The accompanying drawings form a part of this specification and illustrate the invention.

Figure 1 is a side elevation of the device with the hand-lever slightly elevated. Fig. 2 25 is a plan view of the same. Fig. 3 is a side elevation with the lever brought to a horizontal position.

Similar letters of reference indicate corresponding parts in all the figures.

30 The post or standard A and the lift B may be made of some suitable wood combining required strength with lightness. The top of the lift is notched or stepped to enable it to pass under and operate on different heights 35 of axles, two or more of these steps b being provided, according to the width of the lift or the range of adjustability to be given to the jack. The faces of these steps are shod with iron plates b', to prevent wear and breakage.

40 That portion of the post which the lift works on is reduced in thickness, so as to give lightness with a suitable margin of strength; and the part below, forming foot of the standard, is carried of full width, nearly equal to the width 45 of the lift above it, to give proper stability. At the top and bottom ends of the lift a strap, D, is secured in position to embrace the standard and slide smoothly upon it as vertical movement is given to the lift, and against one

side of the standard, at a point between the two straps, the operating-lever E is pivoted. This lever, while made of any required length, has its inner end formed into a broad and flat head; somewhat of a curved shape, so as to give increased breadth at this part around 55 and above the fulcrum, and it is carried out beyond the standard and behind the fulcrum, so as to extend along the side of the lift. The object of this construction is twofold: first, to afford different points of attachment on the 60 head for the outer end of the link G, by which the position or angle of inclination of the lever can be kept as nearly as possible to the horizontal at the time the lift is set up; and, secondly, to give a brace or support along and 65 against the side of the link, so that no lateral pressure or strain derived from any unequal weight on the end of the lift shall act directly upon the link. This gives a very strong connection of the lift and standard without the 70 necessity of employing cheek-pieces, ribs, and grooves, or other construction to prevent lateral movement.

In such kinds of lifting-jacks where its position, when in use, frequently renders it difficult 75 to reach and work the hand-lever with sufficient application of force to bring the lift to the required height, I find a great advantage is obtained by making the connection of the end of the curved link with the lever at such 80 point that when the lift is raised to the required height the three points will be brought into line at the time the lever approaches a horizontal or nearly horizontal position. In such case the force required to raise the weight can 85 be more directly and effectively applied than in other constructions where the outer end of the lever requires to be pressed down nearly to the ground, because the difficulty of applying pressure increases as the end of the lever 90 passes beyond the horizontal line. The end of the curved link can be attached to the lever at several different points, h, which are provided in the enlarged head of the lever above its fulcrum, so that a longer or shorter movement can be given to the lift, according as one 95 or the other of the steps or notches is brought into service.

Having thus fully described my invention, what I claim, and desire to secure by Letters Patent, is—

The herein-described lifting-jack, consisting of the standard with its foot, the stepped lift, the straps connecting said lift to the standard, the pivoted lever having the enlarged head projecting beyond the standard and against the side of the lift, and the curved link at-

tached to the lift at one end, and having adjustable attachment to the lever at points above the fulcrum thereof.

Witness my hand and seal.

TRUMAN J. PEARCE. [L.S.]
